United States Patent Office

Des. 181,275
Patented Oct. 29, 1957

181,275

EJECTION SEAT

Clifford B. Cooper, Fort Worth, Tex., assignor to General Dynamics Corporation, San Diego, Calif., a corporation of Delaware

Application July 18, 1955, Serial No. 36,993

Term of patent 14 years

(Cl. D15—8)

FIG. 1

FIG. 2

Figure 1 is a front perspective view of the ejection seat, illustrating my new design;

Figure 2 is a rear perspective view of the seat taken from the opposite side from that shown in Figure 1.

I claim:

The ornamental design for an ejection seat, substantially as shown.
